Inventor,
Bela I. Sommers;
By Wilbur M. Stone
his Attorney.

UNITED STATES PATENT OFFICE.

BELA I. SOMMERS, OF TUCKAHOE, NEW YORK, ASSIGNOR TO SNYDER & BLACK, INCORPORATED, OF NEW YORK, N. Y., A CORPORATION OF NEW YORK.

COLLAPSIBLE DISPLAY DEVICE.

Application filed January 5, 1923. Serial No. 610,817.

To all whom it may concern:

Be it known that I, BELA I. SOMMERS, a citizen of the United States, and a resident of Tuckahoe, in the county of Westchester and State of New York, have invented certain new and useful Improvements in Collapsible Display Devices, of which the following is a specification.

This invention relates to collapsible display devices and has for its object to provide a device of the character specified, of simple construction and employing a minimum of material for the purpose.

With these ends in view and others which will appear later herein my improvements comprise features illustrated in their preferred embodiment in the drawing accompanying this specification, wherein:

Figure 1 is a front perspective view of the device in erected display condition. Fig. 2 is a plan view of the blank which may be folded into the form of Fig. 1. Fig. 3 is a fragmentary rear perspective view of a portion of what is shown in Fig. 1, illustrating the construction and assembly. The figures of the drawing are to substantially one scale.

My display device is directed to the representation of a plurality of boxes, cartons or the like arranged corner to corner in a horizontal row, or of a plurality of stacks of such articles, and preferably arranged in pyramidal form. The device may be formed from a unitary blank of approximately rectangular contour having vertical score lines for defining the several vertical panels or sides of the boxes represented, there being only two vertical sides of each box required in accordance with my improvements. In Fig. 2 blank B has a horizontal base 2, opposite end edges 3, 4, and vertical score lines, as 5, 6, 7, 8, defining the several upright sides of the several boxes represented. In the illustrated form of my improvements each vertical element represents two boxes or cartons of the same size, one upon the other as C¹, C² of stack C, Fig. 1. The next stack, D, represents two similar boxes D¹, D², of larger size than those in the first stack, and the third stack, E, which may be the middle stack, is of still larger size both transversely and in height, whereby a pyramidal effect is had.

In Fig. 2, between edge 3 and score

line 5 is front wall 9 of the first stack of boxes, C, and between score lines 5 and 6 is end wall 10 thereof, and between score lines 6 and 7 is front wall 11 of the second stack, D, and between score lines 7 and 8 is end wall 12 thereof, and so forth. For defining the top walls of the several stacks, transverse score lines, as 13 to stack C, extend across both panels or sides as 9, 10 of the blank, a distance from the top of said blank equal to the width of end wall 10, and from said score line 13, upwardly, the blank is cut through on lines 5^a, 6^a, said lines being the upward continuation of score lines 5, 6, respectively.

The top wall of each section, as 14 of stack C, is provided with an upwardly extending tab 15, having its root at score line 16 inset a certain distance from the top edge of wall 14. Also each section is provided with a flap, as 17 upstanding from panel 10 and which may for convenience be of equal height with top wall 14 and is provided near its right hand edge 6^a with slot 18. Said slot is located from edge 6^a a distance sufficient to provide a substantial wall 19 between said slot and edge 6^a, and tab 15 has its root 16 inset from the top edge of wall 14 a distance equal to the distance of slot 18 from edge 6^a.

In erecting the device in display position, panel 9, is folded backwardly along line of articulation 5 into approximately right angle relation to panel 10, and flap 17 is folded downwardly into right angle relation to panel 10, then tab 15 is folded back along line 16 at right angles to top 14 and said top is folded down to cause tab 15 to enter slot 18 in flap 17, and finally against said flap, into right angle relation to the vertical sides of the box. Then end 10 is folded forwardly along line 6 and the erection of the second section, D, of the display is proceeded with as just described in connection with section C. The other sections may then be similarly erected. The details of assembly will be clearly understood by reference to Fig. 3.

There is thus produced a display device representing a plurality of complete boxes or stacks of boxes in diagonal relation, by the employment of three panel members only for each box or stack, and which display will stand without extraneous support,

and which may be simply erected or knocked down into flat form for packing.

I claim:

1. A collapsible display device including in combination a plurality of horizontally arranged upright panels articulated together and folded along their lines of articulation for alternately representing the front and end walls of a plurality of boxes or stacks of boxes respectively, flaps articulated to the upper edges of alternate panels, top walls articulated to the upper edges of those alternate panels between the panels to which the flaps are articulated, and coacting means on said flaps and top walls for interlocking when said flaps are folded at an angle to their respective panels and said top walls folded thereover for representing the tops of said boxes and for holding the display in erected position.

2. A collapsible display device including in combination a plurality of horizontally arranged upright panels articulated together and folded along their lines of articulation for alternately representing the front and end walls of a plurality of boxes or stacks of boxes respectively, flaps articulated to the upper edges of alternate panels, top walls articulated to the upper edges of those alternate panels between the panels to which the flaps are articulated, a slot near one edge of each of said flaps, and a tongue on each of said top walls having its root inset from an edge thereof a distance equal to the distance of one of said slots from its contiguous flap edge, said tongues being adapted for entering said slots when each pair of said flaps and top walls are folded into substantially one plane respectively, for

representing the tops of said boxes and for holding the display in erected position.

3. A blank adapted for folding into a display device including in combination a plurality of horizontally arranged panels articulated together along vertical parallel lines, for alternately representing the front and end walls of a plurality of boxes or stacks of boxes respectively, flaps articulated to the upper edges of alternate panels, top walls articulated to the upper edges of those alternate panels between the panels to which the flaps are articulated, and coacting means on said flaps and top walls for interlocking when said flaps are folded at an angle to the respective panels and said top walls folded thereover.

4. A blank adapted for folding into a display device including in combination a plurality of horizontally arranged panels articulated together along vertical parallel lines, for alternately representing the front and end walls of a plurality of boxes or stacks of boxes respectively, flaps articulated to the upper edges of alternate panels, top walls articulated to the upper edges of those alternate panels between the panels to which the flaps are articulated, a slot near one edge of each of said flaps, and a tongue on each of said top walls having its root inset from an edge thereof a distance equal to the distance of one of said slots from its contiguous flap edge, said tongues being adapted for entering said slots when each pair of said flaps and top walls are folded into substantially one plane respectively.

In witness whereof, I hereby affix my signature this 4 day of January, 1923.

BELA I. SOMMERS.
